UNITED STATES PATENT OFFICE.

HENRY BERGER, OF NEW YORK, N. Y.

DESIGN FOR CENTER-PIECE.

Specification forming part of Design No. 7,854, dated November 10, 1874; application filed October 28, 1874.
 [Term of Patent 14 years.]

To all whom it may concern:

Be it known that I, HENRY BERGER, of the city, county, and State of New York, have invented a new and original Design for Center-Piece, of which the following is a specification:

This invention consists in the design of a basket filled with fruit which overhangs the rim thereof, said basket being suspended by four ribbons inside of a panel having curved ends and sides, and having corners surmounted with birds. The above is inclosed by a frame of twigs or branches having arched ends, triangular arched corners, and straight sides, the ends and sides being ornamented with bunches of corn, wheat, and hops.

The invention is illustrated in the accompanying drawing, which represents a face view of my design.

The letter A designates the central portion or basket of my design, which is filled with fruit, represented as overhanging the edge of the same, the fruit being interspersed with leaves, and the whole being so disposed as to form an oval wreath, B, around the basket. The basket is suspended by four ribbons, a, on a panel, C, in the rear of the basket, a portion of the ends and sides of the panel being curved inward and outward, respectively, and the four corners thereof being surmounted with figures D of birds with spread wings. E is

the rim or frame surrounding the panel, which is made to resemble twigs or branches, and the ends of which are arched, while the corners are arched and triangular and the sides are straight. Outside of this frame E are ears or bunches of corn, wheat, and hops intermingled with each other, and with husks and leaves, as shown.

By these characteristic features I produce a design of a highly ornamental and distinguishing appearance.

What I claim as new, and desire to secure by Letters Patent, is—

1. The design of the basket A, filled with fruit, as shown and described.
2. In combination with the basket A, the panel C, as shown and specified.
3. The combination, with the basket A and panel C, of the frame or border E, as shown and set forth.
4. The bunches F of corn, wheat, and hops, in combination with the frame E, panel C, and basket A, as shown and described.

In testimony that I claim the foregoing I have hereunto set my hand this 6th day of August, 1874.

HENRY BERGER.
